UNITED STATES PATENT OFFICE.

ALFRED WILLIAM SOUTHEY, OF LONDON, ENGLAND, AND JOSEPH J. MEGIRIAN, OF NEW YORK, N. Y.

COMMINGLING-PUMP FOR CARBONATORS.

No. 833,257.

Specification of Letters Patent.

Patented Oct. 16, 1906.

Application filed January 8, 1906. Serial No. 295,146.

To all whom it may concern:

Be it known that we, ALFRED WILLIAM SOUTHEY, a subject of the King of Great Britain, residing at London, England, and JOSEPH J. MEGIRIAN, a native of Turkey, residing at New York city, State of New York, have invented certain new and useful Improvements in Commingling-Pumps; and we do hereby declare that the following is a full, clear, and exact description of the invention, which will enable others skilled in the art to which it appertains to make and use the same, reference being had to the accompanying three sheets of drawings, illustrating one form of our invention and forming part of this specification, in which corresponding parts are designated by similar marks of reference, and in which—

Figure 1 is a central vertical section on line A A in Fig. 4. Fig. 2 is a central vertical section on line B B in Fig. 4. Fig. 3 is a central vertical section on line C C in Fig. 4. Fig. 4 is a top plan view of the apparatus, and Fig. 5 is a panoramic vertical section on circular line D D in Fig. 4 imagined cut at d and straightened out.

The object of our invention is to provide a simple and efficient apparatus more or less automatic in action and operation for thoroughly commingling a certain quantity of a liquid or liquids with a certain quantity of a gas or gases, preferably for immediate use, and relates more particularly to that class of pumps or apparatus of this or a similar nature in which the two or more substances to be intimately commingled at least one of these is at a pressure sufficiently greater than the other or others as to be able to furnish the power required for effecting in a satisfactorily rapid and thorough manner, first, the drawing in of the substance or substances of lesser pressure; second, the commingling of the different substances; third, the discharging of the liquid so charged with gas immediately following their union and as needed.

A further important advantage possessed by our commingling-pump is the circumstance that if utilized, for example, to furnish carbonated or "sparkling" beverages and employing for this purpose and as an actuating medium carbonic-acid gas or other suitable gas stored as customary in containers at a comparatively high pressure or

when similarly actuated with liquid or compressed air such gas, performing work during its expansion in the apparatus, is thereby lowered in temperature to a considerable degree, and thus capable of cooling the liquid so acted upon without the use of ice or snow.

Referring now to the drawings, in a double-acting cylinder 1, preferably arranged vertically, a piston 2 is secured to a hollow tubular piston-rod 3 by means of nuts 4 and 5. This piston-rod 3 is closed at its free or lower end by means of a screw-plug 6, to which is attached one end of a flexible band 7, the other end being secured to a drum 8, upon which this band 7 may be wound. Drum 8 is loosely mounted on a stationary spindle 9, round which it may turn freely. A suitable spring 10 is contained within drum 8, the inner end of which is secured to spindle 9 and the outer end to drum 8, arranged and adjusted in such a manner as to at all times exert a pull on the band 7, which causes the piston to be in its highest position within the cylinder when the pump is not in operation. A casing 11 houses drum 8 and piston-rod 3, the latter passing through a stuffing-box 12 and packing 13. Secured to the upper cylinder end 14 and reaching downward into tubular piston-rod 3, passing freely through nut 5, is a tube 15, open at its lower end and its upper end communicating through conduit 16 with conduit 17. The latter connects valve-chambers 18 and 19. A conduit 20, provided with an adjustable pressure-reducing valve 21, serves to admit gas under pressure from a container (not shown) to valve-chamber 18, while valve-chamber 19 communicates through conduits 22 and 23 with the space y within the cylinder below the piston 2.

Valves 24 and 25, secured to valve-stems 26 and 27, respectively, are adapted to close the two ends of conduit 17 when being depressed. Valve 29, secured to valve-stem 36, is adapted to establish communication between the space y below piston 2 and the container (not shown) for the liquid to be acted upon by the gas through conduit 28, valve-chamber 30, and conduit 31. The liquid is ordinarily at atmospheric pressure or at a pressure considerably below the pressure of the gas employed, which enters the pump through conduit 20. Valve 32, secured to

valve-stem 37, is adapted to permit the discharge of the contents of the space x above the piston within the cylinder whenever this piston is forced upward through valve-chamber 33, conduit 34, and spout 35. An adjustable safety or relief valve 43, Fig. 3, held to its seat by a spring, is provided to establish communication between conduit 17 and the atmosphere through conduits 44 and 45 whenever the pressure in the apparatus exceeds a permissible maximum. Cam-disk 39, rotatably mounted on screw-stud 38, carries on its lower surface a circular cam 40, arranged concentrically, which simultaneously engages the upper ends of valve-stems 36, 27, 37, and 26, Fig. 5. These valve-stems are preferably arranged equidistant, in the above instance ninety degrees apart, and carry valves 29, 25, 32, and 24, respectively. The circular cam 40 is provided with two projections and two depressions arranged alternately and ninety degrees apart to engage the four valve-stems, those shown opposite always being similar in position.

The operation of our commingling-pump is as follows: Assuming that conduit 20 is brought into communication with a source of a gas under high pressure—carbon dioxid, for example—while conduit 28 communicates with a vessel containing a liquid—water, milk, beer, fruit-juice, &c.—to be carbonated. If then cam-disk 39 is turned horizontally by means of handle 47, so as to place valves 24 and 25 in the position shown in Fig. 1, the gas entering conduit 20 has to pass valve 21 to be reduced in pressure to the desired extent and to prevent its rushing into the apparatus too quickly, flowing then through valve-chamber 18 and conduits 17 and 16 into and down tube 15, thence into and up tubular piston-rod 3, entering the space x within the cylinder above the piston 2, through openings 46 in the upper part of nut 5. In this manner a certain pressure is exerted against the upper side of piston 2, with the result that this piston is forced downward, thereby forcing the liquid contents in space y below piston 2 out through conduits 23 22, valve-chamber 19, and conduits 17 and 16 into and down tube 15, thence into and up tubular piston-rod 3, and through openings 46 in the upper part of nut 5 into space x above piston 2. From this is seen that the two streams of gas and liquid meet in conduit 16 to flow together through tortuous passages into space x , thereby most thoroughly and intimately commingling. Since the pressure per square inch in the spaces x and y is the same, it is obvious that the effective area must be greater in x than in y , which is accomplished by making tubular piston-rod 3 of sufficiently large diameter. The liquid in space y had been drawn in throughout the preceding upstroke. During the downstroke

of piston 2 the tubular piston-rod 3, to the lower end of which band 7 is fastened, partly unwinds the latter from drum 8, thereby increasing the tension of spring 10 to such an extent that when at the end of the down-stroke cam-disk 40 is turned ninety degrees from the position shown in Figs. 1, 2, and 5 this spring is capable of forcing up piston 2, thereby drawing a fresh supply of a liquid into y while discharging the carbonated contents of x through valve-chamber 33, conduit 34, and spout 35. The valves and the passages controlled by them are preferably arranged in such a manner that by turning cam-disk 40 but forty-five degrees from the position shown in the drawings both ends of conduit 17 may be closed, as well as conduits 28 and 34, for the purpose of avoiding a high pressure in the pump when not in actual operation. Should, however, the pressure within this apparatus increase beyond a certain predetermined point, relief-valve 43, spring-loaded as may be required, will permit the escape of part of the contents of space x through conduits 16, 44, and 45. Of the four cam-operated valves only valve 29 is provided with a spring 41, confined by rim 42, to under all circumstances secure contact between the cam and valve-stem 36, while the remaining valve-stems are forced against the cam by the pressure of the contents of the apparatus.

We have found by experiment that by admitting to an apparatus of the character described gas at as high a pressure as the same is carried in steel containers and causing expansion to take place within this apparatus the great reduction in temperature thus made possible causes not only a more thorough and intimate but also a more permanent commingling of the different substances introduced, which is of importance when carbonating liquids.

Having described our invention, what we claim as new, and desire to secure by Letters Patent, is—

1. In a commingling-pump having a cylinder divided into two chambers by a piston having different pressure areas, a valved gas-inlet to the chamber having the greater piston area, a valved fluid-inlet to the other chamber, a valved inlet connecting both chambers, and a valved outlet from the chamber having the greater piston area, all valves controlled by a cam member.

2. In a commingling-pump having a cylinder divided into two chambers by a piston having different pressure areas, a valved gas-inlet to the chamber having the greater piston area, a pressure-reducing valve in said inlet, a valved fluid-inlet to the other chamber, a valved inlet connecting both chambers, and a valved outlet from the chamber having the greater piston area, all valves controlled by a cam member.

3. In a commingling-pump having a cylinder divided into two chambers by a piston having different pressure areas, a valved gas-inlet to the chamber having the greater piston area, a valved fluid-inlet to the other chamber, a valved inlet connecting both chambers, and a valved outlet from the chamber having the greater piston area, all valves controlled by a cam member, together with means for storing piston-return power during the expansion-stroke.

In testimony whereof we have signed our

names to this specification in the presence of the subscribing witnesses.
